[57] CLAIM

The ornamental design for a vehicle clearance lamp, as shown and described.

DESCRIPTION

FIG. 1 is a front perspective view of the vehicle clearance lamp of my invention;

FIG. 2 is a front elevational view of the vehicle clearance lamp illustrated in FIG. 1 with the rear elevational view being a mirror image thereof;

FIG. 3 is an end elevational view of the left side of the vehicle clearance lamp, the right side being a mirror image thereof;

FIG. 4 is a top plan view of the vehicle clearance lamp illustrated in FIG. 1;

FIG. 5 is a bottom plan view of the vehicle clearance lamp illustrated in FIG. 1;

FIG. 6 is a front perspective view of a first alternative embodiment of the vehicle clearance lamp of my invention;

FIG. 7 is a front elevational view of the embodiment of the vehicle clearance lamp illustrated in FIG. 6, the rear elevational view of the vehicle clearance lamp being a mirror image thereof;

FIG. 8 is an end elevational view of the left side of the vehicle clearance lamp illustrated in FIG. 6, the right side being a mirror image thereof;

FIG. 9 is a top plan view of the embodiment of my vehicle clearance lamp illustrated in FIG. 6; and,

FIG. 10 is a bottom plan view of the embodiment of my vehicle clearance lamp illustrated in FIG. 6.
